INTERNAL TUBE PULLER

Glenn Edwards, Memphis, Tenn.

Application April 19, 1948, Serial No. 22,009

1 Claim. (Cl. 294—96)

1 This invention relates to pipe or tube pullers. An object of this invention is to provide a puller whereby pipes or tubes formed of relatively soft metal may be removed from their supporting plates without damage to the tube or to the plate. As an example, condenser tubes are usually formed of copper, brass or other soft metal, and as the outer ends of these tubes are swedged or upset to seal the tubes in the supporting or head plates, it is a difficult matter to remove the tubes without damage thereto or to the head plate. In the case of boiler tubes it is also quite difficult to pull the tubes without damage thereto. It is, therefore, an object of this invention to provide a tube puller which will firmly grip the tube from the inside thereof in such a manner that the tube will not be injured and at the same time the gripping force will increase in proportion to the pulling force and to the resistance of the tube.

Another object of this invention is to provide a puller of this kind wherein the pulling force is in axial alignment with the axis of the tube and of the clamping or gripping means so that the latter will not be tilted under the action of the pulling force.

A further object of this invention is to provide a puller of this kind which will readily conform itself to the size and shape of the tube.

With the above and other objects in view, my invention consists in the arrangement, combination and details of construction disclosed in the drawing and specification, and then more particularly pointed out in the appended claim.

In the drawing,

Figure 1 is a detailed side elevation of a pipe or tube puller constructed according to an embodiment of this invention, showing the puller in its initial inserted position with respect to the pipe or tube.

Figure 2 is a fragmentary side elevation partly in section, of the device in pulling position.

Figure 3 is a detailed inner end elevation of the device.

Figure 4 is a fragmentary sectional view taken on the line 4—4 of Figure 1.

Referring to the drawing, the numeral 10 designates generally a tube which is mounted in a plate of head 11, the tube 10 being extended through an opening 13 in the head or plate 11 and the outer end of the tube 10 being upset as indicated at 12. The tube 10 may be of the type used in condensers or the like and in such devices the tube 10 is formed of metal such as copper, brass or the like.

In order to provide a means whereby the tube

2 10 may be pulled from the plate 11 without injury to the tube, I have provided a puller which includes complementary tube clamping or gripping members 14 and 15. These clamping members 14 and 15 are of elongated construction and as shown in Figure 1 the clamping member 14 is of tapering construction and has the larger end 16 thereof innermost. The clamping member 15 has a small end 17 thereof innermost and when the flat confronting faces 18 and 19 of the clamping or wedging members 14 and 15 are disposed in contacting relation, the two clamping members 14 and 15 will be substantially round in transverse section as a unit.

15 The clamping member or wedge 15 is secured to a block 20 having an elongated handle 21 extending right angularly therefrom. The outer end of the clamping member 14 is secured to a block 22 and the two blocks 20 and 22 are formed with confronting flat faces 23 and 24 respectively. The block 22 comprises the movable portion of the wedge assembly and has secured thereto a hook 25 embodying a relatively long shank 26. The hook 25 is so disposed with respect to the two blocks 20 and 22 that when a pulling means is engaged with the hook 25, the pulling force will be substantially in a plane collinear with the longitudinal axis of the tube 10.

The outer or peripheral surfaces of the clamping members 14 and 15 are of like construction and are formed of blunted threads 27, thereby forming spiral surfaces 28 adapted to engage the inner surface of the tube 10. The provision of the flat surfaces 28 eliminates any cutting of the interior of the tube as the wedge member 14 is pulled outwardly and tightly wedges itself and wedge member 15 within the tube 10. The inner ends of the wedge members 14 and 15 are provided with smooth portions 29 and 30 respectively which form a plug of a diameter slightly less than the interior diameter of the tube 10. These smooth portions 29 and 30 are designed to remove any scale or the like which may be disposed in the tube 10 so that when the wedge members 14 and 15 are disposed in wedging position they will contact with the metal of the tube 10 instead of any scale or accumulation on the inside of the tube. In other words, the plug members 29 and 30 form a means for scraping the interior of the tube 10 as they are moved inwardly to operative position.

In the use and operation of this device the two blocks 20 and 22 are disposed in face abutting relation with the wedge members 14 and 15 in contacting relation as to their flat faces 18 and

19. These wedge members 14 and 15 are inserted in the tube 10 to the limit provided by the blocks 20 and 22 as shown in Figure 1. The handle 21 will provide a means whereby the small wedge member 15 may be manually held against movement during the initial pulling of the device so that when the hook 25 is pulled and wedge member 14 moves outwardly a slight distance to a position substantially as shown in Figure 2, the wedge member 15 will not move with wedge member 14. As a pulling force is applied to the hook 25 and to the movable wedge member 14, a tight gripping or clamping force will be applied to the interior of the tube 10 so that the gripping surfaces 28 of the wedge members will tightly grip the inner surface of the tube. The tube is pulled endwise after the manner shown in Figure 2 and due to the relatively long gripping surfaces provided by the wedge members 14 and 15, the pulling force required for removing the tube 10 will not distort or expand the tube.

This tube puller has been placed in practical operation and has been found to more readily remove tubes from condenser walls or plates than prior devices and at the same time the tubes will not be damaged and if necessary may be reinserted in the condenser walls. It will, of course, be understood that this puller may also be used for pulling other tubes such as boiler tubes or the like, as well as condenser tubes.

I do not mean to confine myself to the exact details of construction herein disclosed but claim all variations falling within the purview of the appended claim.

What I claim is:

A tube puller comprising a pair of oppositely tapered wedge members adapted for insertion within a tube, each of said members having an arcuate outer surface and a flat inner surface, the inner surfaces of said members in confronting and contacting relation and on an angle to the longitudinal axes of said members, the outer surface of each member being formed with spiral 5 threads having blunted peaks, an enlarged block 10 having a securing handle extending horizontally therefrom fixed to the large end of one of said members, and a second enlarged block fixed to the small end of the other of said members and 15 formed with a connector extending longitudinally thereof for connecting the latter to a pulling means, the inner end of the outer surface of each member being smooth and formed to provide a scraping edge at substantially right angles 20 to the longitudinal axis of its associated member.

GLENN EDWARDS.
